WALL ALTAR

Stanley Laskowski, Beaver Falls, Pa.

Filed Nov. 13, 1961, Ser. No. 67,496

Term of patent 3½ years

(Cl. D29—23)

FIG. 1

FIG. 2

FIG. 1 is a front perspective view of a wall altar showing my new design; and

FIG. 2 is an enlarged fragmentary front elevational view thereof.

The broken line showings in FIGURE 1 are for illustrative purposes only.

I claim:

The ornamental design for a wall altar, as shown and described.
